UNITED STATES PATENT OFFICE.

EMILIE ELSA MÜLLER, OF CHEMNITZ, GERMANY.

ROUND-KNITTING MACHINE.

Application filed February 7, 1925, Serial No. 7,596, and in Germany February 14, 1924.

This invention has reference to round knitting machines generally and in particular to the so-called pearl-knitting machines by means of which hosiery like goods and other knitted fabrics generally of substantially tubular shape is manufactured which is intended as wearing apparel and should be so shaped and manufactured that it will substantially assume the configuration of the shape of the human body. In the pearl-knitting machines as heretofore suggested by the previous art, it was the usual course to effect the reduction or enlargement of the diameter in jumpers, skirts, sweaters, gaiters and the like by the usual reduction or diminishing of the meshes, or by alternately loose and fast knitting, with the inconvenience, however, that this resulted in a distortion of the proportions of the several constituent parts of the pattern itself, while, on the other hand, the manufacture of such goods from ordinary flat or tubular knitted fabric by the cutting-out and subsequent combination of sections required a previous stretching and the use of a model for the preparation of the several parts and the union thereof.

With my invention this difficulty is overcome by a novel construction of pattern-producing knitting loom by means of which it is possible to combine the pattern fabric with additional knitted portions, which by a kind of tension produce the same result as has been obtained heretofore by the reduction or diminishing of meshes.

In the round-knitting machines as heretofore constructed for patterned goods and operating with or without jacquard for all pearl-goods with superimposed single cylinders and double-tongue needles cooperating therewith, it has been possible to manufacture smooth pearl and patterned goods. This kind of manufacture, however, failed to produce the tubular goods referred to and adapted to hug the human body.

Now, in accordance with this invention it becomes possible to manufacture the goods referred to, such as cuffs, gaiters, four-in-hands, ties, stocking shafts, sleeves, gloves, sweaters, bodices and stays, caps, jumpers, ladies' skirts and other garments and the like in the regular manner and without seam.

The device is shown in the accompanying drawing by way of exemplification, in Fig.

1 partly in elevation and partly in longitudinal section through a round knitting machine in accordance with my invention with the needles and sinkers shown diagrammatically only by way of clearness of illustration; in Figs. 2-8 the cooperation of the needles with the draft sinkers and pushing sinkers is illustrated, Fig. 2 is an aggregation of four different views showing the sinkers in different positions with relation to the double-hooked needle and respectively in side view and front view and Figs. 3-8 are vertical longitudinal sections through the wall of the machine for the better illustration of the operation of the sinkers and consecutively corresponding to the section lines $v-w$ to $ee-ff$ from right to left of Figure 1. Fig. 9 illustrates diagrammatically the connection of a jacquard apparatus of ordinary construction with the knitting machine. Fig. 10 indicates diagrammatically another construction of the usual knitting lock and Figs. 11 and 11^a show respectively side elevation and front view of another modification illustrating the use of a dividing comb employed in place of a jacquard for the raising and lowering of the sinkers.

Broadly speaking, the new feature of the invention as compared with the previous art may be indicated as follows: The two single cylinders P are arranged above each other and are composed of several portions and comprise sliding surfaces or guides D and E along which the draft sinkers G, which are provided with correspondingly inclined surfaces, are adapted to move. By means thereof the sinker G is moved immediately above the operating needle J into a position adapted for the direct engagement or disengagement with the operating needle to be displaced. The pushing sinker F, which is disposed below or adjacent the movable engageable or disengageable draft sinker G, is adapted to move with the latter in the vertical direction. The pushing sinker may operate directly upon the operating needle, so as to move the same into the central inoperative position indicated in Fig. 2 in which position the securing of the stitches has already taken place. By this means it is possible by the pressure of the weak cards of the jacquard to securely and reliably operate the sinkers for the operation of the needle. This operation takes place by the direct ac-

tion of the sinkers and without the intermediate sinkers usually employed.

Referring more particularly to the other figures of the drawings, Fig. 1 is a sectional view of the round pearlizing knitting machine cylinder P with one of the needles J in the operative position, thread guide Q, needle tooth opener R and needle lock S, N the upwardly pointing arrows indicating in a conventional manner the operation of the needles in the direction of the arrow. On the lefthand side of the drawing at I the sinker and needle bar H is shown mounted in the case C and with the sliding surfaces D and E for the sinkers G. On the right-hand side of the drawing at II the sinkers F and G are shown, the draft sinkers being indicated at G and the pushing sinkers at F in their positions of rest with relation to the sliding surfaces D and E and in the disengaged position.

The needles controlling locks S are constructed in such a manner that in the operating lock of the lower group of needles the sinkers F and G are adjusted to be constantly operated, while otherwise the arrangement is such that with the operating lock of the upper group of needles only the sinkers F and G are adapted to be engaged with or operated and pulled by the jacquard apparatus, Fig. 9, or an equivalent means, by the cord K or the like. The jacquard or other pattern-producing member is flexibly connected to the pulling sinker jack G, but inasmuch as the two sinker jacks F and G are in engagement with each other by means of their angularly projecting feet L, M the pulling of the sinker jack G will also carry along the pushing sinker jack F.

Now, referring more particularly to the figures of the drawing which correspond to the second section indicated in Fig. 1, I would say that in Fig. 2 the pushing sinker is indicated generally at F, while the draft sinker is indicated at G, in side view at 1, 1 and in plan view at 2, 2, also showing the pushing shoulders T and the pushing lugs. Fig. 3 shows the pushing sinker F and the draft sinker G in side view, corresponding to section V—W.

Fig. 3 shows the position of the operating needle J and of the lower sinkers F and G in the position of rest, while the upper sinkers F and G have been pulled by the cord K of the jacquard apparatus or equivalent means, the draft sinker G being at the same time positioned along the sliding surfaces D and E ready for engagement with their operating needle J and in the depressed position, whereupon the draft sinker G is raised together with the pushing sinker F.

Fig. 4 is a side view, with parts in section, corresponding to section X—Y (Fig. 1) with the sinkers F and G elevated by the

action of the lock section N (Fig. 1), the operating needle J having been pulled thereby, while the lower draft sinker G, being contrary to the arrangement of the upper sinkers in engagement with the lower needle-controlling lock, as above set forth, is disengaged from the operating needle J and is engaged by the substantially cam-shaped lower lock section S.

Fig. 5 is a side view with parts in section, corresponding to section AA—BB of Fig. 1, showing the parts in reverse position with relation to Fig. 4, and with the upper sinkers F and G in the inoperative position, so as not to be affected by the jacquard apparatus, while the lower sinkers F and G, which are controlled as above set forth by the lock S, are adapted to become engaged and pull the operating needle J. Those of the sinker-jacks in the upper cylindrical needle bed which have not been pulled by the jacquard or similar pattern-making member will be operated upon in the usual manner by the cam-like lock member S, N.

Fig. 6 is a side view with parts in section corresponding to sectional line CC—DD showing the position of the sinkers with the operating needle J in a position of securing the stitches, these stitches as seen in the direction of the arrow being in the inverted position with relation to the other stitches that is to say pearlizing stitches or stitches turned for the purpose of forming a pattern.

Fig. 7 shows the parts in the inverted position with relation to Fig. 6 and with the operating needle J in the lower cylinder P disposed for the fastening and securing of the stitches.

Fig. 8 is a side view with parts in section corresponding to sectional view EE—FF of Fig. 1 in which the lower sinkers F and G have already assumed their inoperative position while the upper sinkers F and G are in the position in which the pushing sinker is adapted to push the operating needle in the direction towards the lower sinkers F and G so as to restore the parts to their position of rest.

Fig. 9 shows a well-known jacquard apparatus of conventional manner in side elevation with cords K, being adapted to pull the stitches into the operating position in accordance with the position and the configuration of the jacquard cards.

Fig. 10 illustrates an auxiliary lock section adapted to be employed in a modification of my invention in place of the jacquard apparatus for adjusting the sinkers by means of the auxiliary lugs O, preferably secured to the upper parts of the sinkers.

Figs. 11 and 11^a show a part of another modified construction showing a portion of a dividing comb for engagement with the lugs O by means of which the sinkers may be

adjusted in accordance with the pattern desired and made to engage with the operating lock N.

- The arrangement may be such that, while the upper portion of the machine in which only those sinkers adapted for the working of the pattern are in engagement with the controlling locks of the needles, is called upon to produce the figuring or fancy pattern of the goods, all the sinkers of the lower cylinder bar, as hereinbefore set forth, are in engagement with the lock portion of the particular lower machine section and are arranged to produce the rows or other figures on which the variation of tension of the fabric depends for producing the reduction or enlarging, similar to the effect hereinbefore obtained by the usual lessening or diminishing of stitches or equivalent means.
- These rows or stitches may preferably be arranged in such a manner as to extend in a parallel direction or transversely with relation to the pattern and at the outside or within the same. The engagement of the pushing and draft sinkers may be such that the draft sinkers or the like in their descent move along their guides past the pushing sinkers and along a corresponding guiding portion of the same, while upon the pulling of the draft sinkers the pushing sinkers become free to drop past the draft sinkers to be engaged with the needle in their turn.

Within the scope of my invention I also contemplate arranging the tension producing rows or stitches of the knitted fabrics in other directions, and I may say in conclusion that the invention is susceptible of various other modifications and alterations to answer other purposes and to suit different working conditions, without thereby deviating from the scope and spirit of my invention as defined in the appended claims.

I claim:—

1. In a round knitting machine the combination with a needle bed of inclined guides on said bed and a plurality of angularly offset sinker jacks adapted to slide along said guides and a plurality of double-ended hooked needles in axial alignment with said jacks and engageable therewith.

2. In a round knitting machine the combination with a needle bed of partly straight and partly inclined vertical guides on said bed, a plurality of substantially straight sinker jacks movable along said guides, and an inclined portion on each of said jacks engageable with the inclined part of the guides and a plurality of double-ended hooked knitting needles in axial alignment with said jacks and engageable therewith.

3. In a round knitting machine the combination with a needle bed of partly straight and partly inclined vertical guides on said bed, a plurality of substantially straight sinker jacks movable along said guides, an

inclined portion on each of said jacks, engageable with the inclined part of the guides, a substantially cam shaped needle lock adapted for engagement with certain of the jacks, and a plurality of double-ended hooked knitting needles in axial alignment with said jacks and engageable therewith.

4. In a round knitting machine the combination with a needle bed of partly straight and partly inclined vertical guides on said bed, a plurality of pairs of adjacently disposed respectively pushing and pulling sinker jacks, having inclined portions intermediate their ends and movable in said guides, lateral angularly projecting feet on said jacks, a plurality of double-ended hook needles in axial alignment with said jacks and with their hooked ends disposed between the ends of the pushing and pulling sinker jacks, and cam shaped needle locks engageable with the feet of certain of the pairs of jacks.

5. In a round knitting machine the combination with a needle bed of vertical straight and partly inclined guides on said bed, a plurality of pairs of adjacently disposed respectively pushing and pulling sinker jacks with inclined intermediate portions movable in said guides, respectively superimposed lateral angularly projecting feet on each of the pairs of jacks, a plurality of substantially double-ended hook needles in axial alignment with said jacks catching means at the needle-confronting ends of the pulling jacks and engageable with the hooked needle ends, and moving means for the jacks.

6. In a round knitting machine the combination with a needle bed of vertical straight and partly inclined guides on said bed, a plurality of pairs of adjacently disposed respectively pushing and pulling sinker jacks with inclined intermediate portions movable in said guides, respectively superimposed angular projections on each jack of the pairs, a cam shaped needle lock engageable with certain of said pairs, a pattern working device, flexibly connected to the pulling jacks, a plurality of substantially double-ended hook knitting needles in axial alignment with said pairs of jacks and with their ends disposed between the jack-ends of the particular pair, and catching means at the free ends of the pulling sinkers, engageable with the needle hooks.

7. In a round knitting machine the combination with an upper and a lower needle bed and a plurality of substantially double-ended hook knitting needles, vertically displaceable and adjacently disposed at the confronting ends of said needle beds, a plurality of vertical straight and intermediate inclined guides on said beds, a plurality of pairs of adjacently disposed respectively pushing and pulling sinker jacks

with inclined intermediate portions movable in said guides in axial alignment with the needles, inter-engaging angular projections on each jack of the pairs, a cam shaped 5 needle-lock in the lower needle bed, adapted for engagement with the projections of the lower pairs of sinker-jacks, a cam shaped needle lock on the upper needle bed, engageable with the projections of certain of the 10 lower pairs of jacks, a pattern working member, flexibly connected to the upper pulling jacks, and needle-engaging terminal portions on said sinker-jacks respectively above and below the hook-shaped needle 15 ends and engageable therewith.

8. In a round knitting machine the combination with a needle bed of a plurality of partly straight, and partly inclined vertical guides on said bed, a plurality of pairs 20 of adjacently disposed respectively pushing

and pulling sinker jacks with inclined portions intermediate their ends and movable in said guides, a plurality of substantially double-ended hook knitting needles in axial alignment with said jacks, a pushing extension 25 on the needle confronting end of the pushing sinkers, and a substantially hooked extension on the needle confronting end of the pulling sinkers, said extensions respectively disposed above and below the needle-end, and engageable therewith, inter-engaging projections on the jacks of each pair and near the needle-engaging ends thereof, means to move said sinkers, and cam-shaped 30 guiding means engageable with said projections.

In testimony whereof I have signed my name to this specification.

EMILIE ELSA MÜLLER.
